[57] CLAIM

The ornamental design for a clip-on earphone, as shown and described.

DESCRIPTION

FIG. 1 is a front, top and side perspective view of the clip-on earphone showing my new design;

FIG. 2 is a left side elevational view thereof, the right side being a mirror image;

FIG. 3 is a front elevational view thereof;

FIG. 4 is a rear elevational view thereof;

FIG. 5 is a top plan view thereof; and,

FIG. 6 is a bottom plan view thereof.

The cord which is shown in FIGS. 1, 2, 5, and 6 is broken away to indicate indeterminate length.

FIG. 1.

FIG. 4.

FIG. 2.

FIG. 5

FIG. 6.

FIG. 3.
